Des. 235,010
Patented Apr. 29, 1975

235,010

MOTORCYCLE FAIRING

Daniel Hugon, 38 Rue Pasteur, Moirans-en-Montagne,
Jura, France

Filed May 24, 1973, Ser. No. 363,560

Term of patent 14 years

Int. Cl. D12—11

U.S. Cl. D12—182

FIG. 3

FIG. 4

FIG. 1 is a front perspective view of a motorcycle fairing showing my new design;

FIG. 2 is a side elevational view thereof;

FIG. 3 is a top plan view thereof; and

FIG. 4 is a bottom plan view thereof.

I claim:

The ornamental design for a motorcycle fairing, as shown.
